UNITED STATES PATENT OFFICE.

RICHARD A. CROMWELL, OF WOODSVILLE, NEW HAMPSHIRE.

DESIGN FOR A CIGAR LIGHTER.

Application filed December 4, 1928. Serial No. 29,106. Term of patent 7 years.

To all whom it may concern:

Be it known that I, RICHARD A. CROMWELL, a citizen of the United States, and a resident of Woodsville, in the county of Grafton and State of New Hampshire, have invented a new, original, and ornamental Design for a Cigar Lighter, of which the following is a specification.

Reference is to be had to the accompanying drawings, in which

Fig. 2 is a top plan view thereof.

I claim—

The ornamental design for a cigar lighter as shown.

Signed at Woodsville in the county of Grafton and State of New Hampshire this 27th day of November, A. D. 1928.

RICHARD A. CROMWELL.
